UNITED STATES PATENT OFFICE.

LEWIS H. JOHNSON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,256,698.

Specification of Letters Patent. Patented Feb. 19, 1918.

Application filed May 25, 1917. Serial No. 170,859.

To all whom it may concern:

Be it known that I, LEWIS H. JOHNSON, a citizen of the United States, residing at Bloomfield, in the county of Essex and 5 State of New Jersey, have invented certain new and useful Improvements in Telephone-Exchange Systems, of which the following is a full, clear, concise, and exact description.

10 This invention relates to telephone exchange systems, and more particularly to such systems in which both common battery and magneto or local battery lines terminate at a central office at which there are connecting circuits for establishing connections between such lines.

The object of this invention is to provide improved signaling means for systems of this character.

20 In accordance with a feature of this invention, an operating circuit is completed for a signaling device when the subscriber of the connected line, whether magneto or common battery, rings off or restores the receiver to the switchhook, thereby causing a signaling device associated with a universal connecting circuit to furnish a signal of one indication. The same signaling device, upon the subsequent removal of the receiver from the switchhook by the subscriber of a connected common battery line, is intermittently operated to furnish a signal of another indication, thereby enabling the operator to distinguish between disconnect 30 signals and recall signals.

In systems heretofore used in which connections are established with magneto lines as called lines, it is necessary to actuate a ringing key to connect the source of ringing current to the line for operating the call bell. This, the operator does, and then waits a short time before actuating a listening key to connect the operator's telephone set therewith to learn whether the called subscriber has responded. If the subscriber has not responded the ringing key must again be operated to again ring the call bell of the wanted line. In these systems now in use, it is possible that the operator may actuate the 40 ringing key and later, thinking that the called subscriber had not been signaled, may again actuate the ringing key without first actuating the listening key to determine whether the subscriber has responded. If

the subscriber has the receiver to his ear 55 when the ringing key is thus again actuated, the source of ringing current is connected in circuit with the receiver, and, therefore, results in ringing in the subscriber's ear, which is very disagreeable. In a system embodying the present invention, by causing the operation of a signaling device when the ringing key is first actuated, which signaling device remains operated until the listening key is subsequently actuated, the operated or non-operated condition of this signaling device serves to keep the operator fully advised as to whether the ringing or listening key was last actuated, so that there is less probability of ringing the subscriber 70 in the ear.

For a more complete understanding of this invention, reference should be had to the following specification, taken in connection with the accompanying drawing in which 75 there is shown a common battery telephone line A, extending from a subscriber's station to a central office, and a magneto or local battery telephone line B, extending from a subscriber's station to the central office. At 80 the central office there is located a cord circuit C of the universal type for interconnecting subscribers' lines. This cord circuit may be employed for connecting together two magneto lines or two common battery 85 lines or a magneto and a common battery line. It is believed that the nature of this invention is such that it will be fully understood from the description of the operation of the system disclosed in the drawing; 90 hence, it will be so described.

The subscriber of a line A initiates a call in the usual manner, causing the lighting of the line lamp 5, in response to which the operator inserts answering plug 6 into line jack 7. Relays 8 and 9 and cutoff relay 10 are thereupon operated over a circuit from battery through the winding of relay 8, left-hand winding of relay 9, sleeve contacts of the answering plug 6 and line jack 100 7, and the winding of cutoff relay 10 to ground. Relay 9 operates when either end of the cord circuit is connected with either a common battery or magneto line. Relay 8, however, is marginal and operates when connected in circuit with the low resistance winding of the cutoff relay of a common battery line, but does not operate when con-

nected in circuit with the high resistance winding of a cutoff relay of a magneto line. Relay 8, in operating, connects battery to the cord circuit, through the windings of supervisory relay 11, which now operates over the line. Upon the actuation of the supervisory relay 11, relay 12 is operated over a circuit from battery through the contact of relay 9, normal contact of listening key 13, winding 5 of relay 12, normal contact of relay 14, alternate contact of supervisory relay 11, and answering supervisory lamp 15 to ground. The winding of relay 12 is of high resistance so that the supervisory lamp does not light when in circuit therewith. The operation of relay 12 connects relay 14 in parallel with the lamp 15, but the relay 14 does not operate while it is shunted by the relatively low resistance lamp 15.

10 The operator may now actuate the listening key 13, connecting the operator's telephone set with the cord circuit. Upon the actuation of this listening key, the normal contact thereof is opened, thereby causing 15 the deenergization of relay 12, which releases its armatures. The operator, upon being advised that the calling subscriber A desires to be connected with a magneto line, for example, line B, restores the listening- 20 key to normal position, and inserts calling plug 16 into line jack 17. Relay 18 is marginal, and does not operate when connected in circuit with the high resistance winding of cutoff relay 20 of the magneto line. The 25 restoration of the listening key to normal permits the energization of relay 12 as before. The operator may now cause the operation of the call bell at station B by actuating a ringing key 25. Upon the actuation 30 of the ringing key 25, contact 26 thereof is closed to cause the operation of a relay 27 over a circuit from battery through contact 26 of key 25, and the winding of relay 27 to ground. Relay 27, in operating, establishes a locking circuit for itself from 35 battery through the contact of relay 9, normal contact of listening key 13, and contact and winding of relay 27 to ground. Upon the operation of relay 27, calling supervisory lamp 35 is lighted over a circuit from battery through the contact of relay 9, normal contact of the listening key 13, contact of relay 27, lower normal contact of relay 10, upper normal contact of relay 36, 40 normal contact of supervisory relay 37, and lamp 35 to ground. This lamp 35 remains lighted until the listening key 13 is actuated to connect the operator's telephone set to the cord circuit, so that the operator may supervise the connection, and, in so doing, determine whether the called subscriber has answered. Relay 27 is released and the lamp 35 effaced upon the actuation of this 45 listening key 13. If the called subscriber 50 has not answered, the listening key is re-

stored to normal, and the ringing key 25 again actuated to again operate the call bell at station B. Upon this reactivation of the ringing key 25, relay 27 is again energized and locked up, and the lamp 35 is lighted. 70 If, when the operator again actuates the listening key, it is found that subscriber B has responded, the ringing key will, of course, not be actuated again.

At the conclusion of the conversation between subscribers A and B, A restores the receiver to the switchhook, causing the deenergization of supervisory relay 11, whereupon answering lamp 15 is intermittently lighted over a circuit from battery through 80 interrupter 38, upper alternate contact of relay 12, alternate contact of supervisory relay 11, and lamp 15 to ground, to thereby furnish a disconnect signal. The deenergization of the answering supervisory relay 85 11 interrupts the shunt about the relay 14, which now operates and locks up in series with relay 12, the locking being controlled by the listening key 13. Relay 14, in operating, connects interrupter 41 to the front 90 contact of answering supervisory relay 11. The subscriber B, in ringing off, gives the crank of generator 39 a short turn, thereby energizing relay 37, which attracts its armatures. Upon the energization of relay 37, 95 relay 36 is actuated over a circuit from battery through the contact of relay 9, normal contact of listening key 13, winding of relay 36, normal contact of relay 40, alternate contact of relay 37, and the lamp 35 to 100 ground. Relay 36, in operating, establishes a locking circuit for itself from battery through the contact of relay 9, normal contact of listening key 13, winding of relay 36, lower alternate contact thereof, and the 105 winding of relay 40 to ground. As soon as the subscriber quits turning the crank of the generator 39, relay 37 releases its armature, thereby permitting the operation of relay 40, which, however, at this time, performs no useful function. Upon the release 110 of the armature of relay 37, the lamp 35 is intermittently lighted over a circuit from battery through the interrupter 38, upper alternate contact of relay 36, normal contact of relay 37, and the lamp 35 to ground, to furnish a disconnect signal. The operator, in removing the plugs from the jacks in response to the disconnect signals, restores all apparatus to normal position.

Assuming, however, that before the plugs are withdrawn from the jacks, subscriber A removes the receiver from the switchhook to initiate another call. The removal of the receiver from the switchhook by subscriber 125 A causes the energization of answering supervisory relay 11 which causes the intermittent lighting of the answering supervisory lamp 15 over a circuit from battery through interrupter 41, alternate contact of 130

relay 14, alternate contact of relay 11, and lamp 15 to ground. The number of interruptions for a given length of time produced by interrupter 41 is different from 5 that produced by interrupter 38, so that the intermittent lighting of the supervisory lamp 15 upon a recall is at a different rate than when intermittently lighted as a disconnect signal. The operator, in response 10 to the recall indication of the answering supervisory lamp 15, may actuate listening key 13 to connect the telephone set to the cord circuit. In actuating the listening key 13, the normal contact thereof is opened, 15 thereby releasing relays 12 and 14 and effacing the supervisory lamp 15. The connection may now be completed in the manner heretofore described.

In the answering end of the cord circuit 20 C, a ringing key 45 is provided which may be actuated to signal the subscriber of a magneto line if that end of the cord circuit be connected with a line of this character. A relay 46, energized upon the actuation 25 of the ringing key 45, is locked up under control of the listening key 13 and causes the lamp 15 to be lighted until the listening key 13 is actuated.

If the subscriber A had desired to be connected with a common battery line, the insertion of the calling plug 16 into the jack of the common battery line would cause the operation of relay 18 of the cord circuit and the cutoff relay of the line. The operation 30 of relay 18 connects battery through the windings of the supervisory relay 37 to the cord circuit. Upon the operation of relay 18, the calling supervisory lamp 35 is lighted over a circuit from battery through the 35 lower alternate contacts of relay 18, upper normal contact of relay 36, normal contact of calling supervisory relay 37, and calling supervisory lamp 35 to ground. Upon the 40 response of the called subscriber, supervisory relay 37 operates to efface the supervisory lamp 35. Also, upon response of this relay 37, relay 36 is operated. Relays 36 and 40 in the calling end of the cord circuit 45 and C are similar respectively to relays 12 and 14 in the answering end, and function in the 50 same manner.

It is thought that the above description makes the operation of this system entirely clear, and that a further description of the 55 operation in connection with the establishment of a connection between two magneto lines, is unnecessary.

What is claimed is:

1. A telephone exchange system comprising magneto and common battery telephone lines terminating at a central office, a universal link circuit for interconnecting the telephone lines, a signaling device in the link circuit, an interrupter, a relay in the 60 link circuit controlled over a connected line,

either common battery or magneto, to include the interrupter in circuit with the signaling device to cause the signaling device to furnish a disconnect signal, a second interrupter, and relay mechanism serving 70 when the receiver of a connected common battery line is subsequently removed from the switchhook to include the second interrupter in circuit with the signaling device to cause the intermittent operation thereof 75 to furnish a recall signal.

2. A telephone exchange system comprising a telephone line, a link circuit connected therewith, a source of ringing current, a signaling device, a switch for connecting the 80 source of ringing current to the line, a relay energized upon the actuation of the switch to operate the signaling device, an operator's telephone set, and a listening switch for connecting the operator's telephone set to the 85 link circuit and when actuated causing the deenergization of the relay.

3. A telephone exchange system comprising a telephone line, a link circuit connected therewith, a source of ringing current, a 90 switch for connecting the source of ringing current to the line, a signaling device operated upon the actuation of the switch, an operator's telephone set, and a listening key actuated to connect the operator's telephone 95 set to the link circuit and stop the operation of the signaling device.

4. A telephone exchange system comprising a telephone line, a source of ringing current, a ringing key for connecting the source 100 of ringing current to the line, a relay energized upon the actuation of the ringing key, a signaling device operating upon the energization of the relay, an operator's telephone set, and a listening key actuated to connect 105 the operator's telephone set with the line and to deenergize the relay thereby stopping the operation of the signaling device.

5. A telephone exchange system comprising a telephone line, a cord circuit connected 110 with the line, a source of ringing current, a ringing key in the cord circuit for connecting the source of ringing current to the line, an operator's telephone set, a listening key for connecting the operator's telephone set 115 to the cord circuit, a relay energized upon the actuation of the ringing key, a locking circuit for the relay established upon its energization and including a contact of the listening key, a signaling device, and an 120 operating circuit for the signaling device established upon the energization of the relay and including the before mentioned contact of the listening key and a contact of the relay.

6. A telephone exchange system comprising a cord circuit, two telephone lines connected together thereby, a source of ringing current, a ringing key associated with each 125 end of the cord circuit for connecting the 130

source of ringing current to the respective connected lines, an operator's telephone set, a listening key for connecting the operator's telephone set with the cord circuit, a relay for each end of the cord circuit energized upon the actuation of the corresponding ringing key, a locking circuit for each relay established upon the energization thereof, a signaling device controlled by each relay, and an operating circuit for each signaling device established upon the energization of the controlling relay and including a contact of the listening key.

7. A telephone exchange system comprising magneto and common battery telephone lines terminating at a central office, a universal link circuit for interconnecting the telephone lines, a signaling device in the link circuit, a relay in the link circuit controlled over a connected line, either magneto or common battery, to establish an operating circuit for the signaling device to furnish a disconnect signal, a second relay in the link circuit energized upon the energization of the first relay over a connected common battery line, a third relay energized upon the deenergization of the first relay while the second is energized, interrupter mechanism, and an operating circuit for the signaling device and the interrupter mechanism completed upon the subsequent energization of the first relay while the second and third are energized.

8. A telephone exchange system comprising magneto and common battery telephone lines terminating at a central office, a universal link circuit for interconnecting the telephone lines, a signaling device in the link circuit, a relay in the link circuit controlled over a connected line, either magneto or common battery, to establish an operating circuit for the signaling device to furnish a disconnect signal, a second relay in the link circuit energized upon the energization of the first relay over a connected common battery line, a third relay energized upon the deenergization of the first relay while the second is energized, interrupter mechanism, and an operating circuit for the signaling device and the interrupter mechanism completed upon the subsequent energization of the first relay while the second and third are energized.

the first relay and including contacts of the first and third relays.

9. A telephone exchange system comprising magneto and common battery telephone lines terminating at a central office, a universal link circuit for interconnecting the telephone lines, a signaling device in the link circuit, a relay in the link circuit controlled over a connected line, either magneto or common battery, to establish an operating circuit for the signaling device to furnish a disconnect signal, a second relay in the link circuit energized upon the energization of the first relay, a third relay, an energizing circuit therefor including the second relay and completed upon the deenergization of the first relay, interrupter mechanism, and an operating circuit for the signaling device and the interrupter mechanism completed upon the subsequent energization of the first relay while the second and third are energized to furnish a recall signal from a connected common battery line.

10. A telephone exchange system comprising magneto and common battery telephone lines terminating at a central office, a universal link circuit for interconnecting the telephone lines, a signaling device in the link circuit, a relay in the link circuit controlled over a connected line, either magneto or common battery, to establish an operating circuit for the signaling device including a contact of the relay to cause the operation of the signaling device to furnish a disconnect signal, a second relay in the link circuit, an energizing circuit therefor completed upon the energization of the first relay and including a contact thereof and the signaling device, a third relay energized upon the deenergization of the first relay while the second is energized, interrupter mechanism, and an operating circuit for the signaling device and the interrupter mechanism completed upon the subsequent energization of the first relay while the second and third are energized to furnish a recall signal from a connected common battery line.

In witness whereof, I hereunto subscribe my name this 23rd day of May, A. D. 1917.

LEWIS H. JOHNSON.
